Specification of Letters Patent. Patented Aug. 13, 1912.

Application filed September 24, 1908. Serial No. 454,531.

To all whom it may concern:

Be it known that I, FREDERICK MAUSSNER, a subject of Germany, residing at Philadelphia, in the county of Philadelphia and 5 State of Pennsylvania, have invented certain new and useful Improvements in Interwoven-Curled-Hair Mattresses, of which the following is a specification.

My invention relates to improvements in 10 mattresses made of interlaced curled hair, vegetable fiber or the like.

My invention also relates equally to cushions and to articles in which padding is used.

The object of my invention is to construct 15 a mattress by forming an outer surface around the block of material of which the mattress is formed, by interlacing the surface only of said material, which will hold the block of material in its proper form and 20 at the same time allow the material in the interior of the block to remain free from the interlacing and retain its natural resiliency.

A further object of my invention is to continue the interlacing around the edges of the 25 block of material, as well as upon the top and bottom of the block, to hold the same in its proper shape.

A still further object of my invention is to 30 graduate the interlacing by projecting the needles different distances into the block of material, then finishing the structure by going over the entire surface of the block of material and interlacing the outer surface by causing the needles to enter the material 35 a very short distance, thus forming a compact surface which will hold the block in its proper form.

In carrying out my invention I employ a 40 form or mold in which is placed the loose curled hair or vegetable fiber to form a block the size of the mattress or cushion desired.

Heretofore interlaced curled hair mattresses have been made by interlacing entirely 45 through the block of material, which forms a solid structure and causes the curled hair or fiber to lose its natural resiliency making the mattress very compact and hard.

Referring to the drawing: Figure 1. is a 50 perspective view, partially in section, of the completed mattress, made in accordance with my invention; Fig. 2. is a vertical sectional view of the mold containing the material of which the mattress is formed, and 55 showing the needles inserted therein; Fig. 3.

is a view similar to Fig. 2, showing the needles withdrawn, and in the operation of forming the interlacing of the hair; Fig. 4. is a view similar to Figs. 2 and 3, showing the needles set to enter the mattress a uniform distance; Fig. 5. is a vertical sectional view of the mattress and clamping strips used when interlacing the edges of the mattress; and Fig. 6. is a view of one of the needles, detached and drawn on a larger scale. 60 65

In the drawing, 1 represents the mattress formed of a block of interlaced material, such as curled hair.

The loose curled hair 2 is placed in a mold 3, illustrated in Figs. 2, 3 and 4. The mold 70 3 is made the size of the mattress or cushions desired. The needles 5, for interlacing the curled hair, are made of wire with sharp points 6, and provided with barbs 7, as shown in Fig. 6. The needles 5 are arranged in rows and are raised and lowered by any suitable means. The needles are forced into the material, as shown in Fig. 2, and then withdrawn, as shown in Fig. 3. The latter movement of the needles will 80 cause the barbs 7, of the needles, to catch a few strands of the hair and draw them toward the surface of the block of material.

When the needles are withdrawn from the mold, as shown in Fig. 3, the mold is then 85 moved in relation to the needles and the latter are again inserted into the material. This operation is continued until the entire surface of the material has been gone over by the needles and interlaced. This treatment of the hair causes the hair that is drawn toward the surface of the block of 90 material to form a lock with the other hair and hold the block of material compact so that it will retain its proper shape after it 95 is removed from the mold 3.

The needles are entirely withdrawn from the surface of the block of material, as shown in Fig. 3, and are raised sufficiently to be released from the hair that may form 100 in loops around the barbs 7 of the needles. The ends of the hairs will pull off the barbs of the needles and free themselves from the needles, due to the fact that the hair is curled, which causes the hairs to interlock 105 with the hair in the body of the material. The needles simply draw the hairs engaged by the barbs through the body of the surrounding material, causing the interlacing to take place within the block of material 110

and therefore it is not necessary to withdraw the hair in loops and again interloop the same.

To insure the better interlacing of the hair forming the mattress, I vary the depths which the needles enter the material, so that some of the needles will project nearly to the center of the block of material and other needles will project a less distance into the material, the interlacing will thus be graduated from the center of the block toward the outer surface of the block, increasing in density toward the surface of the block of material.

15. The edge of the block of material is clamped between rigid strips 10 and 12 to hold the edge in shape and while thus clamped, the edge of the block of material is passed under the needles and interlaced.

20. All the edges of the block of material are treated in a like manner. It will be seen that a mattress is thus produced which will be composed entirely of the same material and, without any stitching with thread, as 25. the blocks are made the proper size without any cutting.

By graduating the interlacing, the surface of the block of material is firmly held together and it will retain its proper shape. The interior of the block of material is loose and free so that it does not lose any of its natural resiliency.

The block of material is finally passed

under the needles, which latter are adjusted to a uniform height so that they will only enter the surface of the block a very short distance, this final operation insures a more complete interlacing of the hair upon the surface of the block of material.

Having thus described my invention I claim and desire to secure by Letters Patent.

1. An article of manufacture comprising a homogeneous block of loose curled hair, having the material adjacent to the surfaces thereof interlaced to hold said block of material in its proper shape, and the interior of said block of material allowed to remain free from said interlacing and thereby retain its natural resiliency.

2. An article of manufacture comprising a homogeneous block of loose curled hair, having the material adjacent to its surfaces interlaced to hold said block of material in its proper shape, said interlacing extending various distances from the surface of the block of material toward the center thereof, and the interior of said block of material allowed to remain free from said interlacing and thereby retain its natural resiliency.

In testimony whereof I affix my signature in presence of two witnesses.

FREDERICK MAUSSNER.
